**STORAGE HOPPER FOR USE IN AN APPARATUS
FOR SPREADING OR SOWING GRANULAR OR
POWDERED MATERIALS**

Herbert Vissers, Nieuw Vennep, Netherlands, assignor to
Landbouwwerktuigen en Machinefabriek H. Vissers
N.V., Nieuw Vennep, Netherlands, a company of the
Netherlands

Filed May 14, 1965, Ser. No. 85,277

Term of patent 14 years

(Cl. D35—2)

FIG.4

FIG.5

FIG. 1 is a top plan view of a storage hopper for use in an apparatus for spreading or sowing granular or powdered materials showing my new design;

FIG. 2 is a side elevation of the apparatus;

FIG. 3 is a rear view of the apparatus;

FIG. 4 is a perspective view from the front and above the hopper, and

FIG. 5 is a perspective view from the rear and below the hopper.

The broken lines are shown for illustrative purposes only.

I claim:

The ornamental design for a storage hopper for use in an apparatus for spreading or sowing granular or powdered materials, as shown and described.
